DES. 2277

Letters Patent No. 2277. Dated March 6, 1866.

Design for a Trade Mark.

The schedule referred to in this Letters Patent and making part of the same.

To all whom it may concern.

But it is known that A. & S. Lyon, of West Morrisania, in the County of West Chester, and State of New York, have invented a new and improved Design for a Trade Mark, and do hereby declare that the following is a full and exact description thereof, reference being had to the accompanying drawings and to the letters of reference marked theron.

This design consists of the figure of a falcon, with wings outstretched, head depressed, and legs drawn back as in the act of flight. The talons or claws appear just below the line of the front, and the ends of the tail feathers are seen beneath the right wing. Immediately to the right of the figure the word, "Falcon" in Roman capital letters, and the abbreviation "C. & L." in script or Italian letters.

The accompanying drawing illustrates my design for a trade mark as applied to a lead pencil, of the ordinary size and form. When thus applied I propose to add to it a number to indicate the quality or hardness of the lead, but this number forms no part of the design for a trade mark which I desire to secure by Letters Patent.

... claim.

I claim the design for a trade mark as above set forth.

Witnesses.

Thos. P. Horn.
Wm. H. P. Smithson.
